US0D1059125S

(12) United States Design Patent (10) Patent No.: US D1,059,125 S
(45) Date of Patent:  Jan. 28, 2025

(54) CUP

(71) Applicant: YETI Coolers, LLC, Austin, TX (US)

(72) Inventors: Desiree Hunter, Austin, TX (US); Liza Morris, Austin, TX (US); Roy Joseph Seiders, Austin, TX (US); Mark Carlson Rane, Austin, TX (US)

(73) Assignee: YETI Coolers, LLC, Austin, TX (US)

() Term: 15 Years

(21) Appl. No.: 29/813,422

(22) Filed: Oct. 28, 2021
